GESELLSCHAFT, OF ESSEN-ON-THE-RUHR, GERMANY.

PERCUSSION-FUSE FOR PROJECTILES.

1,072,544.

Specification of Letters Patent.

Patented Sept. 9, 1913.

Application filed October 10, 1910. Serial No. 586,272.

To all whom it may concern:

Be it known that I, KARL WIESER, a subject of the Emperor of Germany, and a resident of Bredeney, Germany, have invented certain new and useful Improvements in Percussion-Fuses for Projectiles, of which the following is a specification.

The present invention relates to percussion fuses, suitable for projectiles used in firing against balloons, and wherein the fuse is provided with a lightly movable part protruding beyond the outer limiting surface of the fuse body, the movement of which part produces the ignition, and with a safety-device preventing movement of said part by the action of the inertia on firing, said device being adapted to be automatically released when the projectile commences its flight.

The object of the invention is to provide a fuse of this kind distinguished by having considerably greater sensitiveness than those at present known.

In the drawing is shown one way of carrying out the present invention on a fuse, where the light moving fuse part, projecting beyond the outer limiting surface of the fuse-body, is operated upon by a cheek-brake, which, during the flight of the shot, prevents the light moving part from starting its movement, under influence of the air pressure, which movement would produce the ignition. Fuses of this kind are, for instance described in U. S. Letters Patent No. 988,610, dated April 4, 1911.

35 The accompanying drawing shows in Figure 1, a longitudinal section through the fuse-axis; and in Fig. 2, a top-plan view thereof.

The fuse-part, extending beyond the outer limiting surface of the fuse-body, is provided with a shaft A, which is movable in the direction of the axis of the fuse, and is operated upon by a cheek-brake, the brake of which comprises levers or catches B.

40 The shaft A carries on its outer end a mushroom-shaped hood or cap a', which, as mentioned above, constitutes the arch faced head of the easily movable fuse part. This hood is provided with a plurality of small round 50 openings a² which permit of free passage for the air during the flight of the projectile. The body A a' may suitably be made of very light material as aluminum or wood, so that its inertia would be small. In the trans- 55 porting state of the fuse the shaft A is inter-

locked by a well-known safety-device C, described for instance in U. S. Letters Patent No. 988,610, dated April 4, 1911, said safety-device simultaneously preventing movement of the shaft on firing by the action of inertia and being adapted to be automatically released, when the projectile commences its flight. During the flight of the projectile the shaft is held stationary in the fuse by the pinching of the forward jaws of the levers B around a shoulder on the shaft A caused by the centrifugal force. The rearward jaws of levers B simultaneously engage a collar on the plunger, holding it back against the pressure of a spring. In striking the object, the shaft A moves inwardly, under impact with the target, releases the cheek-brake levers B which then fly outward by centrifugal force, releasing the plunger to the action of a spring, and the plunger then strikes the fulminate, exploding the bursting charge.

As numerous trials have shown, this fuse possesses particularly great sensitiveness. That this is so, can be understood from the fact that, in consequence of the arched surface of the hood a', the contact point of the hood a' with the balloon-cover on striking, is always situated comparatively near the center of the shaft A and that consequently the direction of the force acting at this point always nearly coincides with the direction of the movement of the shaft A so that any lateral pressure on the shaft in its bearing can hardly occur. A fuse of this kind, with a large front surface to its light moving fuse part, will, besides, offer considerably greater resistance (when hitting a mark as easily penetrated as the cover of a balloon) than would an ordinary fuse, in which the surface of the light moving parts act after the manner of a knife edge in striking. The particular advantage is further obtained through the arrangement of the openings a² so that the air-pressure on the cap a', during the flight of the projectile, is diminished and, as a consequence, the resistance of the cheek brake on the shaft A can be kept smaller, whereby the sensitiveness of the fuse will be still more increased. The circumstance, that the apertures a² are situated entirely inside the circumference of the dome a', offers further the particular advantage, that the resistance, opposed to the penetration of the dome by the cover of the

balloon, is not diminished by the arrangement of the apertures. For, if instead of arranging the apertures (a^2) entirely inside the circumference of the dome a' cuts would be arranged on the rim of the dome, the resistance opposed to the penetration of the dome by the cover of the balloon, would be doubtless diminished, as in this case edges would arise on the rim of the dome, which edges would act more or less in the manner of a knife edge, when striking the cover.

I claim:—

1. A percussion fuse for projectiles comprising a substantially easily movable part 15 protruding beyond the outer limiting surface of the fuse body and adapted to effect ignition, and a safety-device preventing movement of said part by the action of the inertia on firing, said device being adapted 20 to be automatically released when the projectile commences its flight, and a contacting domed cap on the outer end of said movable part, the profile of said dome being such as to transmit a practically axial thrust 25 to said part on impact between any portion of the dome's surface with the target, said dome being provided with a plurality of apertures situated entirely inside the circumference of said cap to permit of free 30 passage of air during the flight of the projectile.

2. In a percussion fuse for air ship projectiles having a spring actuated ignition hammer, the combination with checking 35 levers for said hammer, normally restraining the hammer from hitting the primer; of an axially movable member normally holding said levers locked to the hammer;

an external dome shaped head portion on said movable member having a plurality of 40 holes therein for the purpose of giving free passage to the air during flight and to produce a substantially axial thrust on said shaft on impact, said movable member on impact releasing said levers, which actuated 45 by the centrifugal force release the hammer by swinging out, the hammer actuated by its spring subsequently firing the primer.

3. In a percussion fuse for air ship projectiles having a spring actuated ignition 50 hammer, the combination with checking levers for said hammer, normally restraining the hammer from hitting the primer; of an axially movable shaft normally holding said levers locked to the hammer and 55 protruding beyond the front portion of the fuse body; an external mushroom shaped head on said shaft adapted to produce a substantially axial thrust on said shaft on impact at any angle; perforations in said head allowing free passage of air during flight; said levers actuated by the centrifugal force during flight frictionally holding said shaft in its forward position; said shaft 60 on impact releasing said levers which again 65 actuated by the centrifugal force, swing out to release the hammer, the primer being subsequently fired by the hammer actuated by its spring.

The foregoing specification signed at Bar- 70 men, Germany, this 20th day of September, 1910.

KARL WIESER. [L.S.]
